TOY CONTAINER

Martin Sweitzer, Chicago, Ill.

Application April 24, 1933. Serial No. 667,535

2 Claims. (Cl. 46—48)

The present invention relates to toy container, preferably to a combined package and toy which, in the first instance, may be used for containing or enclosing a package of merchandise, and later used as a toy.

5 An object of the present invention is to provide a combined package and toy which may be used as a container for packaged merchandise, and readily converted into a toy vehicle after it has served its purpose as a container.

10 Another object of the invention is to provide a combined package and toy wherein the package is made in the similitude of a railway car having the usual wheels and axles, and in which packaged merchandise may be sold.

15 A still further object of the invention is to provide a combination package and toy which is adapted to contain packaged merchandise during storage, shipment and sale of the same, and is so designed and arranged that, after the package or container has completed its service as such, it may then be quickly converted into a toy vehicle, thus providing a useful purpose for the empty container.

20 25 A yet further object of the invention is to provide a combined package and toy, for containing packaged merchandise, wherein the toy is made in the similitude of a vehicle of approximate shape and outline of the packaged content, and so arranged that the package contents are completely enclosed and protected.

30 35 The above, other and further objects of the invention will be apparent from the following description, accompanying drawings and appended claims.

An embodiment of the invention is illustrated in the accompanying drawings and the views thereof are as follows:

Figure 1 is a side elevational view of a train 40 of cars consisting of packages embodying principles of the present invention.

Figure 2 is an enlarged vertical transverse sectional view taken substantially in the plane of line II—II of Fig. 1.

45 Figure 3 is a fragmental, enlarged, vertical sectional view taken substantially in the plane of line III—III of Fig. 1.

Figure 4 is an enlarged vertical sectional view taken substantially in the plane of line IV—IV 50 of Fig. 1.

Figure 5 is a vertical sectional view taken substantially in the plane of line V—V of Fig. 1.

55 Figure 6 is an enlarged vertical longitudinal view taken through the tank car of the train, illustrated in Fig. 1.

Figure 7 is an enlarged fragmental sectional view taken substantially in the plane of line VII—VII of Fig. 1.

The drawings will now be explained.

The containers or receptacles of the present 60 invention may be made in any suitable form to serve the useful purpose of receptacles of packaged merchandise, and also later as toys, after the merchandise has been removed.

The present invention is exemplified in receptacles made in the similitude of railway cars arranged to be fastened together in a railway train.

Figure 1 illustrates a train of cars, that is a toy train, made up of receptacles of the present 70 invention and embodies a locomotive A, a gondola car B, a box car C, a tank car D, and a caboose E.

The containers of the illustrated form of the invention are shown as adapted for enclosing 75 canned products, such as oil or the like.

The locomotive A comprises a body element 1 and a bottom element 2. These elements 1 and 2 may be made of any suitable material, preferably of inexpensive material, such as tin, stiff cardboard, or other material.

80 The bottom 2 is formed with depending lugs 3, shown with two on each side of the bottom, which lugs are apertured. The body A is, at its lower margin, provided with depending lugs 4 which are arranged to register with the lugs 3, and which are apertured to register with the apertures in the lugs 3.

85 The axles 5 are arranged to be inserted through the apertures in the lugs 3 and 4, which axles carry 90 wheels 6 and 7. The wheels 7 are removably secured to the axles 5, as, for instance, by cotter pins 8 inserted through suitable holes in the axle ends.

The body 1 is removable from the body element 2, by removing the wheels 7 from the axles, 95 withdrawing the axles from the lugs, and then lifting the body 1 from the bottom 2.

The locomotive A is illustrated as enclosing a can 9, the contour of which is substantially that of the contour of the body of the locomotive.

100 A coupling hook 10 is suitably fastened to the bottom 2 for coupling engagement with a car of the train.

The gondola car B is made of inexpensive material, such for instance, as tin or other like sheet metal or stiff cardboard, and comprises a body 11, depending lugs 12, which lugs carry the axles 13 on which are the wheels 14 and 15. The wheels 15 are removably secured to the axles by means 105 of cotter pins 16, or equivalent fastening means.

110

The gondola car B is illustrated as supplied with a can 17 for merchandise. The gondola car B is provided with a coupling hook 18 for purposes well understood.

5 The box car C may be constructed as the locomotive A, or it may have the body 19 permanently associated with the bottom 20. If it is constructed in this manner, then the roof 21 may be hinged at 22 to a portion of the body, for providing access to the interior of the body. When the roof 21 is hinged, as aforesaid, a latch 23 is provided engageable with some part of the outside of the car body, for securing the roof in closed position. The box car C may be supplied 10 with a package 24 having substantially the shape and contour of the box car.

The tank car D comprises a body 29 having portions thereof forming depending lugs 26 for receiving axles 27, which axles in turn carry 20 wheels 28. The body 29 is cylindrical and is secured to the bottom 25 by means of metallic straps 30 surrounding the body and having the ends extending through and bent underneath the bottom 25 of the car. This manner of attaching 25 the straps 30 is illustrated in Fig. 5. The tank car is provided with a suitable coupler 31. The body 29 of the tank car is provided with a removable end 32, whereby access to the interior of the body may be had. The removable end 32 is 30 fashioned as a cap and is frictionally retained within the open end of the body 29. The tank car D is illustrated as enclosing a cylindrical package 33.

The caboose E comprises a bottom 34 supported by wheels 35 carried on axles 36 and engaging suitable lugs fastened and attached to the bottom 34. The body 37, of the caboose, has its lower margin slightly offset outwardly as at 38 to frictionally engage the margin of the bottom 34 and thus retain the body and bottom in assembled association. The caboose E may be supplied with a can such as the cans illustrated in Figures 2, 3 and 4.

The various receptacles herein described and 45 illustrated, afford convenient containers for packaged merchandise, in which the merchandise is offered for sale. When the merchandise has been removed, then the containers become available as toys for the children.

50 The receptacles may be finished in any desir-

able manner of decoration, such as by lithograph, paint, or other form of decoration.

The closed receptacle must of course be provided with means for gaining access to the interior thereof for the purpose of inserting packaged goods as well as for removing such goods from the receptacles. The receptacles of the present invention respond readily to such manner of separation in the body and bottom portions whereby access may be readily had to the interior 85 of the same.

The invention has been described herein more or less precisely as to details, yet it is to be understood that the invention is not to be limited thereby, as changes may be made in the arrangement and proportion of parts and equivalents 90 may be substituted, without departing from the spirit and scope of the invention.

The invention is claimed as follows:

1. A combined toy and package comprising a receptacle made in the similitude of a railway car, said car having a bottom and a closed body for enclosing a package, said bottom having depending apertured lugs for axles, said body having depending apertured lugs for axles disposed 100 to engage the outsides of the first mentioned lugs when said body is mounted on the bottom with the lugs and apertures in register, axles passing through the lug apertures, and wheels on said axles, the engagement of the axles with the 105 apertured lugs constituting the sole means for connecting together said body and said bottom.

2. A combined toy and package comprising a receptacle made in the similitude of a railway car, said car having a bottom and a closed body 110 for enclosing a package, said body having lugs extending below the lower margin of said body, said car bottom having similar lugs extending downwardly therefrom, the body lugs engaging the outsides of the bottom lugs when the toy is 115 assembled, axles carried by said lugs, and wheels removably secured to said axles in such manner that by removal of a wheel from each axle said axles may be removed from said lugs and the body separated from the car bottom, the engagement of the axles with the lugs constituting the 120 sole means for connecting together said body and said bottom.

MARTIN SWEITZER.
